UNITED STATES PATENT OFFICE.

DONALD J. CAMPBELL, OF MUSKEGON HEIGHTS, MICHIGAN.

SAND-MOLDING APPARATUS.

Application filed February 28, 1923. Serial No. 621,233.

To all whom it may concern:

Be it known that I, DONALD J. CAMPBELL, a citizen of the United States of America, residing at Muskegon Heights, in the county 5 of Muskegon and State of Michigan, have invented certain new and useful Improvements in Sand-Molding Apparatus; and I do hereby declare the following to be a full, clear, and exact description of the invention, such as will enable others skilled in the art to which it appertains to make and use the same.

This invention relates to an apparatus for use in molding, being particularly concerned with a machine wherein sand is projected into a flask to fill and pack the same around a pattern in the flask by means of compressed air, one salient feature of the present invention being in the filling of the 15 flask in a plurality or number of projections of sand thereinto, a part only of the sand needed for filling the flask being projected thereinto at each time. Where the flasks are of considerable depth, I have found that 20 in filling the same completely at one discharge of sand under the influence of compressed air, the sand is not packed as closely as it should be particularly in the upper part of the flask. Accordingly, I have devised a construction and method of flask filling wherein a number of projections of sand are made into the flask, getting the required density of sand in the entire mould and making perfect moulds. My invention 25 has for its primary object and purpose the provision of apparatus for effectively carrying out this method of flask filling, various novel constructions and arrangements of parts being provided therefor as will appear 30 from the following description, taken in connection with the accompanying drawings, in which:

Fig. 1 is a front elevation of the apparatus embodying the invention.

Fig. 2 is a horizontal section taken substantially on the plane of line 2--2, of Fig. 1 and looking downwardly as indicated by the arrows.

Fig. 3 is a fragmentary enlarged view, 50 partly in elevation and partly in section, of the sand hopper carrying and controlling means used, and

Fig. 4 is an enlarged vertical section 55 through the machine with the section being from front to the rear thereof.

Like references refer to like parts in the different figures of the drawings.

In the construction of the apparatus a relatively heavy elongated base 1 is provided, at one end of which a post 2 extends upwardly for a distance, above which a screw threaded section 3 is located on which a sleeve 4 is adjustably mounted, being fixed in any place to which adjusted by a binding bolt as shown in Fig. 1. A sleeve or collar 5 is rotatably mounted on and above the sleeve 4, roller bearings indicated at 5^a being interposed between the parts 4 and 5. A cap 6 covers the upper end of the sleeve 5 and a rod 7 extends downwardly through 70 the cap and through the sleeves and posts and may be connected to the base 1 (not shown).

At the opposite end of the base 1, a member 8 is secured above and on which a sleeve or collar 9 is mounted, this collar being located around a post 10 similar to the threaded post 3 previously outlined. A collar 11, like collar 4 is adjustably mounted on the post 10 on the upper end of which a collar 12 is rotatably mounted, a like collar 13 lying over and bearing against the upper end of the collar 12. A covering cap 14 covers the upper end of the collar 13 and a rod 15, similar to rod 7 passes downwardly 80 to the base 1 and may be attached thereto. A cross beam 16 is disposed between the rods 7 and 15, having vertical openings at its ends through which the rods pass. The upper portions of the said rods are threaded 90 and nuts 17 are located thereon one above and the other below the beam, whereby the beam is securely held in place and may be adjusted to different positions, if desired.

The collar 5 is provided with a surrounding block 18 of substantially triangular form, the sides of which make substantially an equilateral triangle (see Fig. 2). At each side a sand hopper carrying yoke of U-shape is secured, each including a part 19 which lies against and is secured to a side of the block 18 and two spaced apart outwardly extending parallel arms 20. The sand hoppers, three in number, associated with said yokes each include an outer frame 100 21 which is positioned between the arms 20 and in front of the part 19. Ears 22 cast integral with the frame have openings there-through for the entrance of pins 23 one of which is carried on the upper side and at 110

the free end of each arm 20 and another on the upper side of the part 19 substantially midway between its ends. The sand hopper frames are accordingly detachably connected to their yoke supports and the same may be slightly elevated with respect to said supports without disconnecting therefrom, as is necessary in the operation of the apparatus, as will later appear. Each hopper is completed by a plurality of cross bars 24 extending between the sides of the frame of the hopper and being in parallelism with the other sides, the bars 24 crossing each other whereby a plurality of openings are made for the passage of sand, but the bars themselves serve as a grate to hold the sand from free passage therethrough. The bars are tapered to an edge at their upper portions and on their under sides are of rounded or curved form as shown.

A bracket arm 25 is permanently secured to the post 2 and extends upwardly and outwardly therefrom, at its free end terminating in a sleeve 26, vertically positioned through which a vertical rod or post 27 freely passes. This post carries a table 28 at its upper end, the upper side of which is grooved or recessed so that it fits closely against and receives the lower edge portions of the bars 24 when elevated against the same as shown in Fig. 3. An arm 26^a is cast integral with the sleeve 26 and extends downwardly therefrom to the lower end of which a lever 29 is pivotally mounted between its ends. One end of the lever has a pivotal connection to the post 27 at its lower end, and to the other end of the lever a link rod 30 is pivotally connected at its upper end, extending downwardly to and having a pivotal connection to a foot pedal 31 which is pivotally connected to a bracket 32 fixed on the base 1 at one end thereof. On depressing the foot lever the table 28 is elevated and may be brought against the under side of any sand hopper which is moved to lie directly over the table, closing the hopper at its lower side or during the time that sand is dropped into the hopper from above, as will later appear, thus stopping any passage of the sand through the hopper.

An integral boss or post 33 extends downwardly from the beam 16 (see Fig. 3), having a ball carrying sleeve 34 fixed therein at its lower end in which a ball 35 is located, normally pressed downward by a spring, as shown. The cap plate 6 has a notch or opening cut in one side for the passage of the lower end of the post 33 to permit the ball to ride against the upper end of the sleeve 5 which, at three equally spaced apart points, is formed with recesses 36 into which the ball 35 may enter. This makes a yielding latch construction for holding the hopper carrying construction in proper positions during the times that the hoppers are

being filled with sand and when they are having the sand forced therefrom by compressed air.

On the upper side of the base 1 and between the posts at the ends thereof, a cylindrical member 37 is secured having an open upper end and screw threaded at its outer sides on to which an interiorly threaded sleeve 38 is screwed. A plate 39 is placed over the upper end of the sleeve 38 and connected thereto from which a downwardly extending guide 40 of cylindrical form passes into the member 37, as shown in Fig. 4.

Ears 41 are formed integrally with the plate 39 and extend upwardly therefrom to which the lower ends of toggle links 42 are pivotally connected, other links 43 being pivotally connected at 44 to the lower links and extending upwardly therefrom and having pivotal connection to ribs 45 on the lower side of a table 46. From this table a relatively long vertical sleeve 47 extends downwardly and is guided through a vertical sleeve 48 formed with the plate 39, it being evident that on straightening of the toggle links, the table 46 is elevated. A rod 49 passes vertically through the sleeve 47 and through an opening in the table, at its lower end having connection to an arm 50 which is fixed on a horizontal shaft 51 mounted to pass through the sides of the member 37, at its outer end having a foot lever or pedal 52 fixed thereto for operation to elevate the rod 49. A protective skirt 53 of sheet metal is attached to the table 46 and extends downwardly to cover the toggle link mechanism, operating means therefore and the devices under the same from sand falling to the same, as shown in Fig. 4.

From the collars 12 and 13 yoke arms 54 and 55 extend terminating in sockets 56 for the reception of trunnions 57 which project outwardly from the sides 58 of flask carrying members, which are completed by bottoms 59 from which the sides extend upwardly. On these bottoms the patterns 60 secured to a base board 61 are secured, and flasks 62 are adapted to be detachably clamped to said boards 61 in the operation of filling the same with sand. It will be noted that the arms 54 and 55 extend upwardly and downwardly at an angle to the horizontal so that the sockets 56 are in the same plane and the bottoms 59 of the flask and pattern carrying members are in the same plane. Said bottoms are each provided with a recess 63 in its under side into which the upper end of the rod 49 may be inserted when a flask carrying member is brought over the table 46, serving to properly locate the flask and hold its carrying member in place for the succeeding operation of flask filling. The flask carrying members are rotatable so that the same may

be turned over, latch members 64 being mounted on one of the arms 54 and 55 of the two yokes adapted to enter openings 65 in a side 58 of the flask carrying members 5 to hold the same in either position to which it is turned.

The flask 62 is adapted to be located on its carrier over table 46 and when in such position the sand hopper frames 21 are moved in succession to positions directly over the upper end of the flask. A rubber gasket or packing member 66 is secured on the under edges of each of the hopper frames 21 so as to come directly over the upper end of the flask to close the joint between the flask and hopper frame when the table 46 is elevated. Integrally formed with the beam 16 is an air reservoir 67, substantially cylindrical in form at the lower end of which is a heavy ring 68 on the under side of which a second gasket 69 is secured for closing the joint between the said ring and the hopper frame 21 which is brought directly under it in position to have the sand projected therefrom into the flask. The ring 68 has its interior space partly filled by a plurality of cross bars 70 of substantially triangular cross section, which cross each other whereby a plurality of passages 71 are made for the escape of air from the air reservoir, said openings progressively enlarging downwardly as shown. Valves 72, one for each passage 71 normally close the upper ends of the passages. All of the valves are carried on a head 73 secured at the lower end of a rod 74 which extends upwardly through the upper end of the air reservoir. Toggle links 75 are pivotally connected together and the lower links pivotally connected to links 76 on the beam 16, the upper ends of the upper links connecting with the rod 74. A member 77 is connected with the knuckle pivot of these toggle links, to which a piston rod 78 is secured, the rod passing into a cylinder 79 and having attachment to a piston therein. Operation of the piston in either direction momentarily raises the head 73 and attached valves 72 and allows the escape of air through the passages 71, as is obvious.

A valve casing 80 has branch pipes 82 leading to opposite ends of the cylinder 79. An inlet pipe 81 carries the air to the valve casing. By means of a suitable valve rotatably mounted in the valve casing the air may be directed to either end of the cylinder. This valve is operable by a lever 83 to the outer end of which a rod 84 is connected, the same having an operative connection with a bar 85 which at its lower end is pivotally connected to one end of arm 86 of a bell crank handle lever, the other arm 87 of which is formed at its free end with a handle for manual operation. The bell

crank lever is mounted for pivotal movement and associated with it is an eccentric 90 movable with the lever, from the lower sides of the housing for which eccentric an arm 88 projects having operative connection 70 with an exhaust valve structure 89 for exhausting the air through the side of the ring 68 after sand projection into the flask has been made. The structure described for controlling the air to the sand hopper is 75 old in a former application for patent by me and forms no part of the present invention and is not specifically outlined in detail for that reason. Only enough is shown to illustrate a practical and operative means 80 for controlling the passage of the air through the passages 71.

An air cylinder 91 has its lower end pivotally connected at 92 to a bracket support 93 fixed to a side of the base 1 and is positioned substantially vertical, as shown in Fig. 4. A piston rod 94 enters the upper end of the cylinder, having connection to a suitable piston within the cylinder and at its upper end is connected to a member 95 at the outer end thereof which at its inner end has connection to the lower pivots of the lower links 42 of the toggle links at the adjacent side of the machine and to the pivot rod 44, whereby on movement of the rod 94 upwardly or downwardly, the links are moved inwardly or outwardly with a consequent lowering or raising of the table 46. A bar 44^a connects the knuckle rods 44 and makes the operation of the 100 toggle links simultaneous.

Air carrying pipes 96 carry air into the upper and lower ends of the cylinder 91, the same connecting with opposite sides of a valve casing 97 to which compressed air is 105 carried through an inlet pipe 98, the exhaust outlet pipe 99 being at the opposite side of the casing. The valve is operated through a lever 100 connected therewith to the outer end of which a link 101 is pivotally connected, extending upwardly and forwardly therefrom and terminating in an operating handle 102 (see Fig. 1), readily accessible from the front of the machine. The air may be directed to either end of the cylinder to either raise or lower the 110 table 46.

The sand for filling the sand hoppers is delivered thereto through an outlet spout 103 at the lower end of a sand holding bin 104, the lower end of the spout being normally closed by closing members 105 pivotally mounted on the spout and having geared connection for simultaneous opening or closing movement. They are normally held closed by the weight shown in Fig. 1 and may be opened by lifting the weight and arm on which it is mounted, allowing sand to fall until the hopper is filled.

An arm 106 extends outward from the 115

sleeve 9, at its outer end terminating in a vertical sleeve 107 in which a post 108 is mounted for vertical adjustment through operation of a handle 109. The post carries a levelling table 110 on to which the filled flask is to be delivered from the flask carrying members of the apparatus. This levelling device also is no novel part of the present invention being fully disclosed in a prior application for patent filed by me.

In the operation of the apparatus, the flask holding member carried between the yoke arms 54 or 55 is brought over the table 46 and centered thereon and properly positioned by bringing the upper end of rod 49 and the recess 63 into conjunction as described. Sand is dropped into a hopper, the table 28 first being elevated against the under side of the hopper, as shown in Fig. 3, the table being then lowered and the hopper moved so as to come directly over the flask and under the air reservoir. This brings another hopper to filling position over table 28 and the same may be filled 25 while the one already filled is being discharged into the flask.

After placing over the flask, handle 102 is grasped and operated to turn air into the cylinder 91 to elevate the table 46. This 30 raises the flask carrying member against the hopper frame and the hopper against the ring 68, compressing the gaskets 66 and 69 and making tight joints so that air cannot escape at the joints. The elevation of the 35 flask carrying members is permitted by reason of the loose bearing of the trunnions in the sockets 56, and the ears 22 on the hopper frame 21 may be raised a short distance on the pins 23 without disconnecting therefrom. 40 The handle 87 may then be grasped and the bell crank operated to lift the valves 72, allowing the discharge of air against the upper side of the sand in the hopper, the sand being projected with force into the 45 flask around the pattern, as is evident.

When one hopper has had its sand discharged, the table 46 is lowered by properly controlling the air passing into cylinder 91, and a second filled hopper brought 50 into place and the operation repeated. After this hopper is discharged, the third one is brought into position and its contents of sand discharged into the hopper. Of course the number of discharges of sand will 55 vary with the depths of the hoppers, but the intent of the invention is to fill the flasks with a plurality of discharges whereby the sand is properly packed in the flask and around the pattern.

60 When a flask is entirely filled, it may be struck off and the flask carrying member with flask attached turned as a whole to above the levelling table 110, the other flask carrying member with empty flask thereon 65 taking the place of the first one. The flask

carrying member is then turned over, inverting the filled flask, the levelling table 110 elevated against the under side thereof and levelled against it, locked in position, the flask unclamped from the board and the 70 table lowered drawing the flask and mould therein from the pattern. In the meantime the other flask is being filled and is brought over the levelling table when filled for taking the flask and mould, the operation being 75 continuous.

The construction is very practical and with it moulds filled with sand of proper density may be produced rapidly and in 80 quantity. A large number of flasks are required, one for every mould made, but otherwise the apparatus requires no additions. Flasks of any desired depth within the limits of the machine may be filled, the plurality of discharges of sand with force into 85 the flask packing and tamping the sand to the required and proper density. The apparatus is easily operated and is practical and efficient in all respects. The appended 90 claims define the invention and I consider the invention to comprehend all forms of construction coming within the scope of said claims.

I claim:

1. In an apparatus of the class described, 95 a support, a movably mounted table on the support, an air reservoir located a distance over the table, a flask carrying member mounted for movement to and away from the table and adapted to carry a flask and 100 pattern therein, a plurality of relatively shallow sand hoppers movably mounted to be moved in succession between the flask and the air reservoir, means normally closing the air reservoir at its lower end, and 105 means for momentarily opening said reservoir at its lower end to project the sand from any hopper into the flask, a plurality of charges of sand from the hoppers being required to fill the flask. 110

2. In an apparatus of the class described, 115 a flask holding member adapted to carry a flask and a pattern therein, a post located at one side of the flask holding member, a collar mounted on the post to turn about the same in a horizontal plane, a plurality of U-shaped yokes projecting from the collar, a sand hopper for carrying sand carried detachably by each yoke and movable into position over the flask, yielding latch means 120 acting on the collar to hold the same against rotation when a hopper is over the flask, and means for applying compressed air to the sand in a hopper to project the same 125 from the hopper into the flask, substantially as described.

3. In an apparatus of the class described, 130 a support comprising a base, spaced apart posts extending upwardly from the ends of the base, a flask holding member mount-

ed on one of the posts to turn about in a horizontal plane, a collar mounted to rotate about the other post, a plurality of U-shaped yokes extending from the collar, 5 a sand hopper frame carried by each yoke, said frame having a grate construction therein to normally hold sand from passing therethrough, a beam disposed between the upper end portions of the posts, a boss extending 10 downwardly from the beam to closely adjacent the upper end of the collar, a spring pressed latching ball carried at the lower end of the boss, said collar having a plurality of ball receiving recesses 15 in its upper end to normally hold the collar against movement when a sand hopper is over a flask on the flask holding member, and means carried by the beam for applying compressed air to the upper 20 surface of the sand in a hopper over a flask to project the sand into the flask, substantially as described.

4. In an apparatus of the class described, a vertical post, a collar thereon, a U-shaped 25 yoke extending horizontally therefrom, said yoke having parallel outwardly projecting arms connected at their inner ends by a cross member, a pin extending upwardly from the end of each arm and also from the cross member at a point between its 30 ends, a sand hopper frame located between the arms and in front of the cross member of the yoke, ears on said frame having openings through which the pins pass, 35 and a grating construction in the lower part of the frame for normally holding sand from passing through the hopper, substantially as described.

5. In an apparatus of the class described, 40 a vertical post, a collar rotatably mounted thereon, a yoke extending horizontally from the collar, a sand hopper frame carried by the yoke and provided with a grating construction at its lower portion, an 45 arm extending outwardly from the post, a rod mounted for vertical movements at the end of the arm, a table at the upper end of the rod shaped to fit the under side of the grating construction in the hopper, 50 and foot operated means for elevating the rod and attached table to bring the table into operative conjunction with the under side of the said grating construction.

6. In an apparatus of the class described, 55 a base, a supporting member thereon, a plate carried on and above said member, a table, toggle link connections between the table and said plate whereby when the links are brought into alinement the table is elevated, a shaft mounted horizontally through 60 said supporting member, a foot pedal on

an end of the shaft, an arm on the shaft within said member, a rod attached to the arm and extending vertically through the table, a flask holding member mounted to move in a horizontal plane over the table and provided with a recess in its under side to receive the upper end of the rod, and means for operating said toggle links to elevate the table, substantially as described. 70

7. In an apparatus of the class described, a base, a vertical cylindrical member attached to the base between its ends, said member being exteriorly threaded, an interiorly threaded sleeve mounted on said member, a plate located across the upper ends of the member and sleeve and formed with a downwardly extending cylindrical guide to enter said cylindrical member and also formed with a vertically positioned 80 smaller guide sleeve substantially central thereof, a table located above the plate, an elongated vertical guide attached to the under side of the table and extending downwardly through said smaller guide sleeve, toggle links disposed between the table and plate, and means for operating said links to raise or lower the table with respect to the plate. 85

8. In an apparatus of the class described, a table, flask and pattern carrying members mounted for movement to and away from the table, a fixed air reservoir located a distance above the table, a plurality of shallow sand hoppers mounted for movement 90 to pass under the air reservoir between it and a flask on the flask carrying member, means for elevating the table to clamp the flask and a hopper between the table and the air reservoir, and means for momentarily permitting the escape of compressed air from the air reservoir to project sand from a shallow hopper into the flask to partly fill the flask, substantially as described. 95

9. In an apparatus of the class described, a base, a table located a distance above the base, a plate supported adjustably by the base between the same and table, toggle links between the plate and table, an air cylinder pivotally connected to the base at its lower end and positioned vertically, a piston rod extending upwardly from the cylinder, means for entering compressed air into either end of the cylinder to move the rod longitudinally in either direction, and means connecting the upper end of the rod with the links for actuating the same to raise or lower the table. 100

In testimony whereof I affix my signature. 110

DONALD J. CAMPBELL. 115
